FIRE EXTINGUISHING APPARATUS

Clarence F. Yost, Ambler, Pa.

Application May 8, 1940, Serial No. 334,053

7 Claims. (Cl. 169—24)

This invention relates to fire apparatus of the portable type and, more particularly to the motor type of engine in which the pumping apparatus is activated from the engine of the truck.

In the majority of instances, the extent of the fire is such that the immediately available supply of water will be sufficient to extinguish it promptly and with little damage to the premises. With the ordinary apparatus, it is necessary to employ for such fires either a chemical apparatus or to connect the fire apparatus with a hydrant or other source of water before any supply can be had at the fire, this, in many cases, resulting in delay and consequent growth of a minor conflagration to one of major proportions.

An important object of the present invention is to provide a fire apparatus including a structure such that a supply of water is immediately available, and without attachment of the apparatus to a hydrant or other source, and which apparatus may be made the source for all necessary hose lines in any but the most extreme cases.

A second object is the provision of an apparatus of this type having means whereby the pressure at the lines may be readily and closely controlled and in which a plurality of different pressures may be simultaneously provided.

Another object of the invention is the production of apparatus of this character which is simple in its construction and operation, and may be readily incorporated in fire trucks of the usual construction.

These and other objects I attain by the construction shown in the accompanying drawing wherein, for the purpose of illustration, I have shown a preferred embodiment of my invention and wherein:

Fig. 1 is a side elevation illustrating fire apparatus constructed in accordance with my invention; and

Fig. 2 is a diagrammatic plan view showing the pump, tank, and manifold connections utilized.

Referring now more particularly to the drawing, the numeral 10 designates a tank of desired capacity, say 500 gallons, which is mounted upon a self-propelled vehicle generally designated at 11, and is provided with an overflow 10a. Associated with the tank at opposite sides thereof are manifolds 12 which may be conveniently arranged at the sides of the body of the vehicle, as illustrated in Fig. 1. Each manifold 12 has at one end thereof, preferably the forward end, a plurality of valved outlets 14 and at its opposite

end a plurality of check-valved inlets 15. Leading from each manifold to the tank 10 is a valved inlet pipe 16, and associated with the tank are low and high pressure pumps 17 and 18 respectively. The low pressure pump has its suction 19 in communication with the interior of tank 10 and its discharge 20 in communication with both of manifolds 12 through a conduit 21 having check-valved communication with the manifolds at 22.

The high pressure pump 18 is provided with an inlet header 23 adapted for connection with the hydrant or other source of water and connected with tank 10 through a valved branch line 24. The discharge 25 of this pump is connected to a manifold 26, the ends of which are provided with one or more valve outlets 27 to which hose lines 28 may be attached. This manifold 26 is connected with manifolds 12 through valved branches 29. Pumps 17 and 18 may, of course, be driven either directly from the motor of the truck 11, or by separate motors, as desired.

It will be obvious that apparatus of this type will be extremely flexible in its operation. Arriving at a fire, pump 17 may be set in operation and hose lines attached to outlets 14 utilized to deliver the contents of tank 10 to the fire. If it appears that the fire is of such serious nature that the contents of the tank will not prove sufficient to extinguish the same, the inlet header 23 of pump 18 may be connected to one or more hydrants to supply additional water, or such hydrants, if available, may be connected to the inlets 15 of manifolds 12. A second engine arriving on the scene may connect an outlet 14 of a manifold 12 to the manifold 12 of the engine first to arrive on the scene, as by connecting line 30, and this procedure may be followed by all succeeding engines. This will render the water carried or supplied by those engines available at the hose lines already laid to the fire, and will avoid the necessity of leading fresh lines thereto. This, in turn, will prevent entanglement and confusion of the lines, and will result in a much more orderly procedure. Through a series of the connections 30, water may be transported for a considerable distance, from a pond or creek, as is often necessary in rural districts where hydrant connections are often not available, or so poorly supplied with water that a sufficient amount cannot be obtained therefrom.

With an assisting engine, or engines, connected to each of manifolds 12, it will be obvious that there will always be available a sufficient amount of water to completely supply hose

lines leading from the several manifold connections of the controlling engine. It will also be obvious that an arrangement of this sort provides great flexibility in the matter of delivered pressures. It is, for example, possible to have three entirely different pressures in the manifolds 12 and the discharge line 26 of pump 18. At the same time, these pressures may be regulated at the controlling engine which first arrived at the fire. If, for example, it is desired to maintain pressures of 100, 80, and 50 pounds and the pressures delivered to the manifolds 12 are 100 pounds on each manifold, the valve line 16 of one of the manifolds may be opened so that the pressure in the manifold is reduced to 80 pounds. Pump 18 may be operated to deliver a pressure of 50 pounds to its manifold 26. It will be understood that at this time the check valves of branches 22 will be closed due to the fact that the pressure in either manifold will exceed the mean pressure delivered by pump 17, and pump 17 is at this time discharging through its relief valve 31 into the tank 10. If the supply to either manifold 12 suddenly fails, pump 17 will immediately become effective to deliver water to that manifold so that there will be no failure of water at the fire, even though the pressure may be somewhat lower than that desired.

The pressure gauges employed, together with the valve systems, enable a single operator to control all discharge pressure and water from the controlling engine, any excess pressure delivered being bled through line 16 into tank 10 and, if necessary, wasting through the overflow 10a.

Since the construction illustrated is, obviously, capable of considerable modification without departing from the spirit of my invention, I do not wish to be understood as limiting myself thereto except as hereinafter claimed.

I claim:

1. In a portable fire extinguishing apparatus, a self-propelled vehicle, a water tank mounted thereon, a pair of manifolds each having a plurality of valve-controlled outlets and at least two inlets, one of said inlets being provided with a check valve and being connectable to an outside source of water, a low pressure pump having its inlet in communication with said tank and its outlet provided with a check valve and in communication with both said manifolds, and a second pump having its discharge in valved communication with both said manifolds and its intake adapted for connection to an outside source of water.

2. In a portable fire extinguishing apparatus, a self-propelled vehicle, a water tank mounted thereon, a pair of manifolds each having a plurality of valve-controlled outlets and at least two inlets, one of said inlets being provided with a check valve and being selectively connectable to an outside source of water or to the outlet of a second apparatus, a valved connection between each of said manifolds and said tank, a low pressure pump having its inlet in communication with said tank and its outlet in communication with both of said manifolds and provided with a check valve, and a high pressure pump having its discharge in valved communication with both of said manifolds and its intake adapted for connection to an outside source of water.

3. In a portable fire extinguishing apparatus, a self-propelled vehicle, a water tank mounted thereon, a pair of manifolds each having a plu-

rality of valve-controlled outlets and at least two inlets, one of said inlets being provided with a check valve and being connectable to an outside source of water, a valve connection between each of said manifolds and said tank, a low pressure pump having its inlet in communication with said tank and its outlet in communication with both of said manifolds and provided with a check valve, and a high pressure pump having its discharge in valved communication with both of said manifolds and its intake adapted for connection to an outside source of water or to said tank.

4. In a portable fire extinguishing apparatus, a self-propelled vehicle, a water tank mounted thereon, a pair of manifolds each having a plurality of valve-controlled outlets and at least one inlet provided with a check valve, said inlets being connectable to an outside source of water, a pump having its inlet in communication with said tank and its outlet provided with a check valve and in communication with said manifolds, and a second pump having an inlet adapted for connection to an outside source or to said tank and an outlet adapted for selective connection to discharge lines or to either or both of said manifolds.

5. In a portable fire extinguishing apparatus, a self-propelled vehicle, a water tank mounted thereon, a pair of manifolds each having a plurality of valve-controlled outlets and at least one inlet provided with a check valve, said inlets being connectable to an outside source of water, valved connections between said manifolds and said tank, a pump having its inlet in communication with said tank and its outlet in communication with said manifolds and provided with a check valve, and a second pump having an inlet adapted for connection to an outside source or to said tank and an outlet adapted for selective connection to discharge lines or to either or both of said manifolds.

6. In a portable fire extinguishing apparatus, a self-propelled vehicle, a water tank mounted thereon, a pair of manifolds each having a plurality of valve-controlled outlets and at least two inlets, one of said inlets being provided with a check valve and being connectable to an outside source of water, a low pressure pump having its inlet in communication with said tank and its outlet provided with a check valve and in communication with both said manifolds, and a relief valve connecting the outlet of said pump between the pump and the check valves of the outlet, with said tank.

7. In a portable fire extinguishing apparatus, a self-propelled vehicle, a water tank mounted thereon, a pair of manifolds each having a plurality of valve-controlled outlets and at least two inlets, one of said inlets being provided with a check valve and being connectable to an outside source of water, a low pressure pump having its inlet in communication with said tank and its outlet provided with check valves and in communication with both said manifolds, a high pressure pump having its discharge in valved communication with both said manifolds and its intake adapted for connection to an outside source of water and a connection between the outlet of the low pressure pump and the tank including a relief valve disposed between the pump and the check valves of said outlet.
